Primary Examiner — Richard E Chilcot(74) *Attorney, Agent, or Firm* — Thomas | Horstemeyer, LLP(57) **CLAIM**

The ornamental design for a cutting machine, as shown and described.

DESCRIPTION

1.1 is a front perspective view of a cutting machine, showing my new design;

1.2 is a rear perspective view thereof;

1.3 is a left view thereof;

1.4 is a right view thereof;

1.5 is a front view thereof;

1.6 is rear view thereof; and

1.7 is a top view thereof.

A bottom view of the cutting machine is not shown because it is featureless and forms no part of the claim design.
